2 SHEETS—SHEET 2.

UNITED STATES PATENT OFFICE.

CHARLES E. WAREAM, OF NORWOOD, OHIO, ASSIGNOR TO THE AMERICAN LAUNDRY MACHINERY COMPANY, OF NORWOOD, OHIO, A CORPORATION OF OHIO.

COLLAR-SHAPER.

1,397,303.

Specification of Letters Patent.

Patented Nov. 15, 1921.

Application filed October 25, 1919. Serial No. 333,228.

To all whom it may concern:

Be it known that I, CHARLES E. WAREAM, a citizen of the United States, residing at Norwood, in the county of Hamilton and 5 State of Ohio, have invented certain new and useful Improvements in Collar-Shapers, of which the following is a specification.

This invention relates to collar shapers. The object of the invention is to provide an 10 improved collar shaper so arranged as to prevent the operator from exceeding a given predetermined ironing pressure on the collar, but which at the same time enables the 15 collar to be ironed with any degree of pressure up to the predetermined normal amount.

A further object of the invention is to provide a collar shaper in which the two 20 ironing members may be locked together in ironing relation with a definite or predetermined normal pressure between them so that the operator while ironing the collar merely produces relative rotating movement 25 between said members, but in which the two members can be readily released from ironing relation in any of their several positions.

A further object of the invention is to provide a collar shaper in which one of the 30 ironing members is self-accommodating to the other or, in other words, has a certain amount of play or movement so that it will naturally adjust itself to any irregularity or different thicknesses of collars.

35 Further objects of the invention are in part obvious and in part will appear more in detail hereinafter.

In the drawings, which represent one suitable embodiment of the invention, 40 Figure 1 is a plan view illustrating the ironing members locked in ironing relation with each other; Fig. 2 is a sectional elevation on the line 2—2, Fig. 1; Fig. 3 is a view similar to Fig. 2, illustrating the ironing members 45 in unlocked or open position; Fig. 4 is a detail sectional elevation on the line 4—4, Fig. 2; and Fig. 5 is a similar view on the line 5—5, Fig. 2.

The collar shaper shown in the drawings 50 comprises a suitable base 1 designed for attachment to a support, such as a table, shelf, or the like. Said base has a depending hollow post 2, the inner surface of which is provided with annular bearing portions 3 55 for a depending hollow sleeve 4 carried by

the base 5 of a collar mold member, the ironing portion of which consists of a circumferential wall 6 extending upwardly from said base 5. Sleeve 4 and the collar mold are vertically slidable in the base, 60 but do not rotate therein. The amount of vertical motion, and particularly the upward motion of the collar mold is limited by a bolt 7 attached to the base 5 and extending through an opening in the base 1, 65 the head of said bolt forming a stop for the purpose mentioned.

Within the sleeve 4 is located a tubular member or shaft 8 which forms a support for the collar ironing member and may also 70 serve as the means through which heat is supplied to the heated ironing member, as will appear. This shaft has a bottom portion 9 rotating in the post 2 and provided on its lower end with a collar 10 which prevents upward movement of said shaft. Shaft 8 is also provided with a collar 11 forming a bottom abutment for a compression spring 12, the upper end of which lies beneath an adjusting thimble 13 80 threaded into the upper end of the sleeve 4 and held in adjusted position by a lock nut 14. With this arrangement the collar mold is always normally pressed upwardly by the spring 12 with a pressure 85 depending upon the position to which the thimble 13 is adjusted, and said thimble enables the pressure to be readily varied to meet any condition.

To the upper end of shaft 8 is secured a 90 horizontally extending guide member 15 having opposite cylindrical end portions 16, 17. On said guide rod is supported the ironing shoe guide bracket 18, having cylindrical portions embracing and rotatable on the 95 end portions 16, 17 of the rod 15, as shown in Fig. 2. Said rod is provided with two lips 19 lying between the end portions of the bracket and which limit longitudinal sliding motion of the bracket on the rod. 100 Also, the bracket may have a longitudinally extending slot 20 in one end in which lies a set screw 21 screwed into the rod. The head of said screw is narrower than the width of the slot 20, as shown in Fig. 5, so 105 that the bracket can rock slightly on the rod for a purpose which will appear.

One end of the bracket 18 is provided with upwardly extending ears 22 connected by a transversely extending rod or shaft 23 which 110

serves as a pivot for a swinging locking or latching member 24. Said member has upwardly extending ears 25 connected by a link 26 to the upwardly extending arm 27 of an operating handle 28, said arm 27 being provided with an upper stop lug 29. Handle 28 is mounted to swing on a shaft 30 supported by ears 31 on the outer portion of an ironing shoe 32, which shoe is provided with two plates 33 pivoted at 34 to the side portions of the bracket 18. Arm 27 has a downwardly extending portion provided with a lower stop lug 35, while the bracket 18 is also provided with a downwardly extending stop lug 36.

Any suitable means may be provided for heating the ironing member, such as by supplying electric current to a resistance element in or near said iron, for example as illustrated in my companion application for collar shaper, filed of even date herewith, Serial Number 333,227. The drawings of the present application, however, show a gas heated iron. In this construction the hollow tubular member 16 is closed at one end and is formed on the other end as a gas burner. The outer end of said burner is adjacent to the inner curved surface 37 of the ironing shoe so that the flame produced by the gas burner is directed upon the ironing shoe. Gaseous mixture is produced by a mixing device 38 of any suitable construction supported by a bracket 39 carried by a collar 40 attached to the bottom of post 2. Said mixer supplies gaseous mixture to the hollow tube 8 which conducts it to the burner, as will be readily understood.

The collar shaper described operates as follows:

Fig. 3 illustrates the unlocked position of the parts. The ironing shoe has been elevated to swing it back out of ironing engagement with the collar mold 6. Said ironing shoe may be held in the unlocked position either by the friction of the adjustable parts, such as by tightening up the pivot screws 34, to the proper amount, or may be normally held upwardly by a light spring. After applying a collar to the mold 6 the handle 28 is pressed downwardly or toward the position shown in Fig. 2. The first downward motion of said handle brings the lower stop lug 35 into engagement with the front wall of the ironing shoe and also initiates a tilting movement of the latch member 24. Continued downward motion of the handle moves the ironing shoe downwardly and into engagement with the collar. When the collar has been engaged by the shoe continued downward motion of handle 28 depresses the mold against the pressure of the spring 12. If desired, the spring 12 can be only partially compressed and the handle rotated around the central vertical

axis in a manner to iron the collar with light pressure. However, if the handle 28 is pressed completely down the locking member 24 finally drops to a position behind a shoulder 40' of the ironing shoe, as illustrated in Fig. 2. In this position the lower end of the ironing member is in engagement with the stop lug 36, so that it is impossible for the operator to produce further downward motion of the iron regardless of the amount of pressure applied to the handle 28. This position, illustrated in Fig. 1, is the normal position in which the collar is ironed by the predetermined ironing position controlled absolutely by the adjustment of the thimble 13.

As the ironing shoe is brought into engagement with the collar, bracket 18 can slide slightly and rotate slightly upon the rod 15, so that it accommodates itself readily to different thicknesses or positions of collars. In releasing the ironing shoe the handle 28 is elevated from the position shown in Fig. 2. The first upward movement of said handle releases the latch 24 from engagement with the shoulder 40', after which the upper lug 29 engages the ironing shoe, whereupon the ironing shoe moves upwardly with the handle to final release position, shown in Fig. 1, and in which the collar can be replaced with another.

What I claim is:—

1. A collar shaper, comprising a collar mold member and an ironing member movable one along the other for the ironing operation, said members also having relative movement toward and from each other, yielding means for producing pressure between said members when in ironing relation, and means for locking said ironing member in ironing relation for movement only in a fixed orbit during locked position.

2. A collar shaper, comprising a collar mold member and an ironing member movable one along the other for the ironing operation, said members also having relative movement toward and from each other, yielding means for producing pressure between said members when in ironing relation, and means for locking said members in ironing relation and arranged to preserve said pressure constant during the locked position.

3. A collar shaper, comprising a collar mold member, a rotating ironing member, said ironing member having movement toward and from said mold member into and out of ironing relation therewith, and latching means for holding said members in ironing relation operated by movement of said ironing member toward said mold member.

4. A collar shaper, comprising a collar mold member, a rotating ironing member, said ironing member having movement toward and from said mold member into and

- out of ironing relation therewith, an operating handle for said ironing member, and latching means for said ironing member operated also by said handle.
5. A collar shaper, comprising a collar mold member, a rotating ironing member, said members having relative movement toward and from each other into and out of ironing relation, yielding means for producing pressure between said members, and latching means coöperating with said members for holding the same in ironing relation under invariable pressure during latched position.
10. 6. A collar shaper, comprising a collar mold member, a rotating ironing member, said members having relative movement toward and from each other into and out of ironing relation, yielding means for producing pressure between said members, a handle for rotating said ironing member and for producing relative approach of said members, and latching means for holding said members in such relation.
15. 7. A collar shaper, comprising a collar mold member, a rotating ironing member, said members having relative movement toward and from each other into and out of ironing relation, yielding means for producing pressure between said members, a handle for rotating the ironing member and for producing relative approach of said members, and a latch operated by said handle and engaging said ironing member.
20. 8. A collar shaper, comprising a collar mold member, a rotating ironing member, said members having relative movement toward and from each other into and out of ironing relation, yielding means for producing pressure between said members, a handle for rotating the ironing member and for producing relative approach of said members, and a latch operated by said handle and engaging said ironing member.
25. 9. A collar shaper, comprising a collar mold member, an ironing member rotatable relative thereto and also having vertical movement toward and from said mold, and a latch member located above said ironing member and adapted to form an abutment for holding said members in ironing relation.
30. 10. A collar shaper, comprising a collar mold member, an ironing member rotatable relative thereto and also having vertical movement toward and from said mold, a latch member located above said ironing member and adapted to form an abutment for holding said members in ironing relation, and an operating handle for actuating both said ironing member and latch member.
35. 11. A collar shaper, comprising a collar mold member, a rotating ironing member,
- said members being relatively movable toward and from each other, an abutment for limiting approaching movement of said members, and latching means for said members effective when said abutment is engaged.
40. 12. A collar shaper, comprising a collar mold member, a rotating ironing member, said members being relatively movable toward and from each other, an abutment for limiting approaching movement of said members, latching means for said members effective when said abutment is engaged, and operating means for said latch movable relative to said ironing member.
45. 13. A collar shaper, comprising an ironing member mounted for ironing movement through a horizontal plane and also for vertical movement to and from ironing position, means for limiting the said ironing member to movement in a fixed path in a horizontal plane while in ironing position, and a collar holding form coöperating with said ironing member.
50. 14. A collar shaper, comprising an ironing member mounted for ironing movement through a horizontal plane and also for vertical swinging movement to and from ironing position, means for limiting the said ironing member to movement in a fixed path in a horizontal plane while in ironing position, and a collar holding form coöperating with said ironing member.
55. 15. A collar shaper, comprising an ironing member mounted for ironing movement through a horizontal plane and also for pivotal movement to and from ironing position, means for limiting the said ironing member to movement in a fixed path in a horizontal plane while in ironing position, and a collar holding form coöperating with said ironing member.
60. 16. A collar shaper, comprising an ironing member mounted for ironing movement through a horizontal plane and also for vertical movement to and from ironing position, means for locking said ironing member against vertical movement while in ironing position, and a collar holding form coöperating with said ironing member.
65. 17. A collar shaper, comprising an ironing member mounted for ironing movement through a horizontal plane and also for vertical movement to and from ironing position, means for automatically locking said ironing member against vertical movement while in ironing position upon moving said ironing member to ironing position, and a collar holding form coöperating with said ironing member.
70. 18. A collar shaper, comprising an ironing member mounted for ironing movement through a horizontal plane and also for vertical movement to and from ironing position, means for limiting the said ironing member

member to movement in a fixed path in a horizontal plane while in ironing position, a collar holding form coöperating with said ironing member, and yielding means for moving said collar holding form toward engagement with said ironing member.

19. A collar shaper, comprising an ironing member mounted for ironing movement through a horizontal plane and also for vertical movement to and from ironing position, means for limiting the said ironing member to movement in a fixed path in a horizontal plane while in ironing position, a collar holding form coöperating with said ironing member, yielding means for moving said collar holding form toward engagement with said ironing member, and means for adjusting the pressure of said yielding means.
20. A collar shaper, comprising an ironing member mounted for ironing movement through a horizontal plane and also for vertical movement to and from ironing posi-

tion, means for limiting the said ironing member to movement in a fixed path in a horizontal plane while in ironing position, a collar holding form coöperating with said ironing member, and yielding means whose pressure is unaffected by movement of said ironing member while in ironing position for moving said collar holding form toward the ironing member to produce ironing pressure.

21. A collar shaper, comprising a support for an ironing member, said support having movement only in a horizontal plane for ironing, an ironing member mounted upon said support and having movement into and out of ironing position, means for locking said ironing member and support together for ironing operation, and a collar holding form coöperating with said ironing member.

In testimony whereof I affix my signature.

CHARLES E. WAREAM.
